ORESTES L. SHEETS, OF MIAMI, FLORIDA

ADVERTISING APPARATUS

Application filed June 30, 1930, Serial No. 464,976. Renewed October 5, 1931.

The present invention relates to advertising apparatus and particularly to a device of this character which is particularly adapted for use in advertising cigars, cigarettes, tobacco, pipes, etc. and has for an important object to provide, in a manner as hereinafter set forth, an advertising apparatus of this character embodying a novel construction and arrangement of parts whereby the attention of persons coming within view thereof will be attracted thereto.

Other objects of the invention are to provide an advertising apparatus of the character described which will be simple in construction, strong, durable, highly efficient in the performance of its intended purpose and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a view in side elevation showing an advertising apparatus constructed in accordance with this invention.

Figure 2 is a fragmentary vertical sectional view through a portion of the device.

Figure 3 is a cross sectional view taken substantially on the line 3—3 of Figure 2.

Referring to the drawings in detail, it will be seen that the reference numeral 1 designates a plate panel which constitutes a sign or bill board preferably showing a representation of a man having a pipe in his mouth as indicated at 2. It is understood, of course, that any desired figure may be represented on the sign or bill board and that a cigarette or cigar may be illustrated in lieu of a smoking pipe. Formed at the mouth portion of the representation 2 is an opening 3 (see Figure 2) which extends through the panel or plate 1. A tube 4 has one end secured to the

plate or panel 1 at the rear side thereof and in communication with the opening 3 by any suitable means such as a flanged thimble 5. The opposite end of the tube 4 is connected to the cylinder of a pump of the reciprocating piston type, said pump being power driven.

Bowl 7 is mounted on its intermediate portion of the tube 4 in which the tobacco or other smoke producing substance is deposited. This is best seen in Figure 2 of the drawings. The portion of the tube 4 which is disposed within the bowl 7 is perforated as indicated at 8.

In operation, the smoke producing material is placed in the bowl 7 as before explained and lighted. When the pump 6 is in operation smoke will be drawn into the tube 4 through the perforation 8 from the bowl 7 on the down stroke of the piston in the pump and on the upstroke of the piston the smoke will be ejected through the opening 3. The piston pipe of pump 6 will eject the smoke in puffs, thus giving the natural effect of a man smoking a pipe.

It is believed that the many advantages of an advertising apparatus constructed in accordance with this invention will be readily understood, and although the preferred embodiment of the invention is as illustrated and described, it is to be understood that changes in the details of construction may be had which will fall within the scope of the invention as claimed.

What is claimed is:—

An advertising apparatus of the character described comprising a flat panel having a representation of a person smoking a pipe cigar or cigarette on one side thereof and further having a transverse opening extending therethrough at a point corresponding to the location of the mouth portion of the representation, a tube rigidly connected to the opposite side of the panel and communicating with the opening, a bowl mounted on the tube at an intermediate portion thereof and

encircling the same, said bowl adapted for the reception of smoke producing material, the portion of the tube within the bowl having perforations therein for the passage of smoke thereinto from the bowl, and a power driven pump of the reciprocating piston type operatively connected to the end of the tube which is remote from the panel, and constituting means for alternately drawing smoke 5 into the tube from the bowl and ejecting said smoke from the tube through the opening in the panel.

In testimony whereof I affix my signature.
